(57) **ABSTRACT**

A construction machine traveling control system is provided. The construction machine traveling control system includes first and second electric traveling pedals for outputting manipulation values including electric signals in response to the driver's manipulation and thereby operating first and second traveling motors connected thereto, respectively; a traveling pattern input means installed in the driving room so as to enable the driver to input a construction machine traveling pattern; a controller electrically connected to the first and second electric traveling pedals and to the traveling pattern input means; and a hydraulic circuit electrically connected to the controller so as to control the flow rate of operation oil supplied to the first and second traveling motors, as well as the flow of the operation oil, according to the command values delivered from the controller.

CONSTRUCTION MACHINE TRAVELING CONTROL SYSTEM

CROSS REFERENCE TO RELATED APPLICATIONS

This application is a 35 U.S.C. § 371 national stage application of PCT Application No. PCT/KR2016/011812 filed on Oct. 20, 2016, the disclosure and content of which are incorporated by reference herein in its entirety.

TECHNICAL FIELD

The present invention relates to a traveling control system for a construction machine and, more particularly, to a traveling control system for a construction machine capable of easily and rapidly changing diverse traveling patterns desired by a driver in connection with a construction machine equipped with electric traveling pedals, such as an excavator.

BACKGROUND ART

In general, two traveling pedals are used for excavator traveling. In this case, one traveling pedal is used to control a left traveling motor and the other traveling pedal is used to control a right traveling motor. For forward or backward traveling, the two traveling pedals are manipulated forward or backward at the same time. However, the simultaneous manipulation on the two traveling pedals for forward or backward movement causes inconvenience to the driver. In particular, when the two traveling pedals are not manipulated by the same amount, the excavator turns left or right, instead of moving forward or backward. Therefore, an additional pedal referred to as a straight traveling pedal is usually equipped and used.

FIG. 7 is a circuit diagram depicting a hydraulic system for excavator traveling in accordance with the related art.

As shown in FIG. 7, the hydraulic system for excavator traveling in accordance with the related art includes a first hydraulic traveling pedal 1a, a second hydraulic traveling pedal 1b, a hydraulic straight traveling pedal 2, a left traveling motor 3, a right traveling motor 4, shuttle valves 5a to 5d and a main control valve 8. Here, the first hydraulic traveling pedal 1a is configured to control the left traveling motor 3, and the second hydraulic traveling pedal 1b is configured to control the right traveling motor 4. Also, the hydraulic straight traveling pedal 2 is configured to control forward and backward traveling. The shuttle valves 5a to 5d are configured to select a signal having a larger value from signals to be applied from the first hydraulic traveling pedal 1a and the second hydraulic traveling pedal 1b and a signal to be applied from the hydraulic straight traveling pedal 2 and to transmit the same to traveling spools 6, 7 of the main control valve 8.

Operations of the hydraulic system for excavator traveling in accordance with the related art are described. A pilot signal pressure applied from the first hydraulic traveling pedal 1a switches the traveling spool 6 via the shuttle valve 5a through a pilot line 9. Thereby, operating oil discharged from a hydraulic pump P1 is supplied to the left traveling motor 3 via the traveling spool 6, so that the left traveling motor 3 is driven. A method of driving the right traveling motor 4 is also the same.

Here, in order to move forward or backward the excavator, the first hydraulic traveling pedal 1a and the second hydraulic traveling pedal 1b have only to be manipulated in

the same direction at the same time. However, the simultaneous manipulation on the first hydraulic traveling pedal 1a and the second hydraulic traveling pedal 1b causes inconvenience to the driver. In particular, when manipulation amounts on the first hydraulic traveling pedal 1a and the second hydraulic traveling pedal 1b are not the same, the pilot signal pressures to be transmitted to the respective traveling spools 6, 7 are different, so that the excavator travels obliquely leftward or rightward, unlike the driver's intention. In order to prevent this problem, the excavator of the related art is equipped with the hydraulic straight traveling pedal 2. A pilot signal pressure that is generated when manipulating the hydraulic straight traveling pedal 2 passes one shuttle valve 5a and the other shuttle valve 5b through a pilot line 10, so that the respective traveling spools 6, 7 are switched at the same time with the same pilot signal pressure. Then, the operating oil discharged from the hydraulic pumps P1, P2 is supplied to each of the left traveling motor 3 and the right traveling motor 4. In this way, the excavator can move forward or backward.

Like this, according to the related art, it is possible to securely move forward or backward the excavator only when the additional straight traveling pedal 2 is equipped. However, the cost of the equipment increases, and the hydraulic circuit for actuation becomes complicated, so that a quality problem such as oil leakage may also be caused.

SUMMARY OF INVENTION

Technical Problem

The present invention has been made in view of the above situations, and an object thereof is to provide a traveling control system for a construction machine capable of easily and rapidly changing diverse traveling patterns desired by a driver in connection with a construction machine equipped with electric traveling pedals, such as an excavator.

Solution to Problem

In order to achieve the above object, according to the present invention, there is provided a traveling control system for a construction machine including first and second electric traveling pedals configured to output manipulation values of electric signals in response to driver's manipulation and to thereby operate first and second traveling motors connected thereto, respectively; a traveling pattern input means equipped in an operator's cab so as to enable a driver to input a traveling pattern of the construction machine; a controller electrically connected to the first and second electric traveling pedals and the traveling pattern input means, and configured to sense the manipulation value to be output from at least one of the first and second electric traveling pedals and the traveling pattern to be input to the traveling pattern input means and to calculate and output command values required for operations of the first and second traveling motors in accordance with the input traveling pattern, and a hydraulic circuit electrically connected to the controller and configured to control a flow rate and flow of operating oil to be supplied to the first and second traveling motors in accordance with the command values to be transmitted from the controller, thereby driving the first and second traveling motors.

The controller may include a memory unit in which a plurality of setting traveling patterns is to be stored, a sensing unit configured to sense the manipulation values and the traveling pattern, and a calculation unit configured to

compare the sensed traveling pattern and the plurality of setting traveling patterns and to calculate the command values to be output to the hydraulic circuit in accordance with the sensed manipulation values so that the first and second traveling motors are to be operated in accordance with a setting traveling pattern, which coincides with the sensed traveling pattern, of the plurality of setting traveling patterns.

Also, the traveling pattern may include a first traveling pattern for moving forward or backward the construction machine in accordance with manipulation on the first electric traveling pedal and turning left or right the construction machine in accordance with manipulation on the second electric traveling pedal.

When the controller senses the first traveling pattern input to the traveling pattern input means and the manipulation value output from the first electric traveling pedal, the controller may calculate a first command value required for the operation of the first traveling motor and a second command value required for the operation of the second traveling motor and transmit the same to the hydraulic circuit, thereby moving forward or backward the construction machine.

Also, when the controller senses the first traveling pattern input to the traveling pattern input means and the manipulation value output from the second electric traveling pedal, the controller may calculate a third command value required for the operation of the first traveling motor and a fourth command value required for the operation of the second traveling motor and transmit the same to the hydraulic circuit, thereby turning left or right the construction machine.

When the controller senses the first traveling pattern input to the traveling pattern input means and the manipulation values output from each of the first and second electric traveling pedals, the controller may calculate a fifth command value required for the operation of the first traveling motor and a sixth command value required for the operation of the second traveling motor and transmit the same to the hydraulic circuit, thereby turning left or right the construction machine, a relative turning speed thereof being increased or decreased as compared to the left turn or right turn of the construction machine in accordance with the third command value and the fourth command value.

The fifth command value may be a sum of the first command value and the third command value.

Also, when the sum of the first command value and the third command value is a positive value, the first traveling motor may rotate in a forward direction, and when the sum is a negative value, the first traveling motor may rotate in a reverse direction.

An electric signal having a magnitude corresponding to an absolute value of the fifth command value may be transmitted from the controller to the hydraulic circuit.

As the sixth command value, a relatively larger command value of the second command value and the fourth command value may be selected.

Advantageous Effects of Invention

According to the present invention, the traveling pattern input means for enabling the driver to select the traveling pattern of the construction machine, such as an excavator and the controller configured to calculate and output the command values required for operations of the traveling motors in accordance with the traveling pattern input from the traveling pattern input means are provided. Therefore, it

is possible to easily and rapidly change the diverse traveling patterns desired by the driver in connection with the excavator. In particular, it is possible to move forward or backward the excavator with only one traveling pedal, so that it is possible to increase driver's convenience and to secure traveling stability.

Also, according to the present invention, it is not necessary to provide a separate straight traveling pedal, unlike the related art, so that it is possible to suppress the additional cost increase of the construction machine.

BRIEF DESCRIPTION OF DRAWINGS

FIG. 1 is a schematic configuration view depicting a traveling control system for a construction machine in accordance with an embodiment of the present invention.

FIG. 2 is a configuration view depicting a controller of the traveling control system for a construction machine in accordance with the embodiment of the present invention.

FIGS. 3 to 6 are graphs showing command values required for operations of traveling motors in accordance with manipulation values of electric traveling pedals.

FIG. 7 is a circuit diagram depicting a hydraulic system for excavator traveling in accordance with the related art.

DESCRIPTION OF EMBODIMENTS

Hereinafter, a traveling control system for a construction machine in accordance with an embodiment of the present invention will be described in detail with reference to the accompanying drawings.

When describing the present invention, the specific descriptions of the related well-known functions or configurations will be omitted if it is considered that the descriptions make the gist of the present invention unclear.

A traveling control system for a construction machine in accordance with an embodiment of the present invention is a system for controlling traveling such as forward movement, backward movement, left turn and right turn of a construction machine, for example, an excavator. As shown in FIG. 1, the traveling control system for a construction machine in accordance with the embodiment of the present invention includes a first electric traveling pedal 11a, a second electric traveling pedal 11b, a traveling pattern input means 12, a controller 13 and a hydraulic circuit 14.

The first electric traveling pedal 11a is configured to output a manipulation value of an electric signal in response to driver's manipulation and to thereby operate a first traveling motor 3 connected thereto. For example, when the first electric traveling pedal 11a is manipulated forward (on the basis of a posture of the driver sitting on a front driver seat) by the driver, the first traveling motor 3 rotates in a forward direction, and when the first electric traveling pedal 11a is manipulated backward, the first traveling motor 3 rotates in a reverse direction. Here, the first traveling motor 3 is configured to be substantially driven by operating oil that is to be supplied from the hydraulic circuit 14 in accordance with the manipulation on the first electric traveling pedal 11a. The first traveling motor 3 may be a track motor configured to drive a crawler type track mounted on a lower traveling structure of an excavator, for example.

The second electric traveling pedal 11b is configured to output a manipulation value of an electric signal in response to driver's manipulation and to thereby operate a second traveling motor 4 connected thereto. The second electric traveling pedal 11b is configured to control the second traveling motor 4 in the same manner as the first electric

traveling pedal **11a**. That is, when the second electric traveling pedal **11b** is manipulated forward by the driver, the second traveling motor **4** rotates in a forward direction, and when the second electric traveling pedal **11b** is manipulated backward, the second traveling motor **4** rotates in a reverse direction. Like the first traveling motor **3**, the second traveling motor **4** is configured to be driven by operating oil that is to be supplied from the hydraulic circuit **14** in accordance with the manipulation on the second electric traveling pedal **11b**, and may be a track motor.

The traveling pattern input means **12** is equipped in an operator's cab. In this case, the traveling pattern input means **12** is preferably equipped at a position at which the driver sitting on the driver seat can perform manipulation with sitting on the driver seat. The traveling pattern input means **12** is configured to enable the driver to input a traveling pattern of the excavator. That is, the traveling pattern input means **12** is configured to enable the driver to select a traveling pattern of the excavator. When the driver selects a desired traveling pattern with the traveling pattern input means **12**, an electric signal relating to the traveling pattern is transmitted to the controller **13** electrically connected to the traveling pattern input means **12**.

traveling pattern is a traveling pattern for rotating the first traveling motor **3** in the forward or reverse direction in accordance with the manipulation on the first electric traveling pedal **11a** and rotating the second traveling motor **4** in the forward or reverse direction in accordance with the manipulation on the second electric traveling pedal **11b**. The traveling pattern may further include diverse traveling patterns so as to widen the options to be selected by the driver, in addition to the first to third traveling patterns.

10 The traveling pattern input means **12** may have a display window so that the driver can select the traveling pattern. In this case, as shown in FIG. 1, the first to third traveling patterns may be displayed as "setting 1", "setting 2" and "setting 3" on the display window of the traveling pattern input means **12**. The display window may be configured by a touch panel so that icons relating to the traveling patterns displayed in this way can be touched and selected by the driver. Also, the traveling pattern input means **12** may be provided with an icon selection button. In this case, the 15 driver can select a desired traveling pattern by manipulating the icon selection button.

10 The controller **13** is electrically connected to the first electric traveling pedal **11a**, the second electric traveling

TABLE 1

Manipulation direction	First traveling pattern	Second traveling pattern	Third traveling pattern
First electric traveling pedal: forward	Excavator: forward movement	Excavator: right turn	First traveling motor: forward direction
First electric traveling pedal: backward	Excavator: backward movement	Excavator: left turn	First traveling motor: reverse direction
Second electric traveling pedal: forward	Excavator: left turn	Excavator: forward movement	Second traveling motor: forward direction
Second electric traveling pedal: backward	Excavator: right turn	Excavator: backward movement	Second traveling motor: reverse direction

Table 1 shows traveling patterns that can be selected by the driver. As shown in Table 1, the first traveling pattern is a traveling pattern for moving forward or backward the excavator in accordance with the manipulation on the first electric traveling pedal **11a** and turning left or right the excavator in accordance with the manipulation on the second electric traveling pedal **11b**. Also, the second traveling pattern is a traveling pattern for turning left or right the excavator in accordance with the manipulation on the first electric traveling pedal **11a** and moving forward or backward the excavator in accordance with the manipulation on the second electric traveling pedal **11b**. That is, since the manipulation manners of the first electric traveling pedal **11a** and the second electric traveling pedal **11b** are determined depending on the traveling pattern, when there are the manipulation manners of the first electric traveling pedal **11a** and the second electric traveling pedal **11b** desired by the driver, the driver can select the corresponding traveling pattern. As can be seen from the first traveling pattern and the second traveling pattern in Table 1, the excavator can be moved forward or backward with only one of the first electric traveling pedal **11a** and the second electric traveling pedal **11b**. Therefore, it is possible to increase driver's convenience and to more stably move forward or backward the excavator. Like this, the change in manipulation manner based on the traveling pattern selected by the driver and the corresponding operations of the first traveling motor **3** and the second traveling motor **4** are controlled by the controller **13**, which will be described later in more detail.

In the meantime, as shown in Table 1, the traveling pattern may further include the third traveling pattern. The third

40 pedal **11b** and the traveling pattern input means **12**. The controller **13** is configured to sense a manipulation value that is to be output from at least one of the first electric traveling pedal **11a** and the second electric traveling pedal **11b**. Also, the controller **13** is configured to sense a traveling pattern that is to be input to the traveling pattern input means **12** by the driver. The controller **13** is configured to calculate 45 command values required for operations of the first traveling motor **3** and the second traveling motor **4** in accordance with the input traveling pattern and to output the same to the hydraulic circuit **14** electrically connected thereto. In the embodiment of the present invention, the command values 50 are defined as magnitudes of electric signals for determining degrees of switching of the traveling spools **6**, **7** (refer to FIG. 7) provided to the hydraulic circuit **14**.

To this end, as shown in FIG. 2, according to the embodiment of the present invention, the controller **13** may include 55 a memory unit **13a**, a sensing unit **13b** and a calculation unit **13c**.

60 In the memory unit **13a**, a plurality of setting traveling patterns is stored. Here, the plurality of setting traveling patterns is the first to third traveling patterns as shown in Table 1. The setting traveling patterns stored in the memory unit **13a** are displayed on the display window of traveling pattern input means **12** so that the driver can select the same.

65 The sensing unit **13b** is configured to sense the manipulation values that are to be output from the first electric traveling pedal **11a** and the second electric traveling pedal **11b** and are to be transmitted as electric signals. Also, the sensing unit **13b** is configured to sense a traveling pattern

that is to be selected and input to the traveling pattern input means **12** by the driver and is to be transmitted as an electric signal by the traveling pattern input means **12**.

The calculation unit **13c** is configured to compare the traveling pattern sensed by the sensing unit **13b** and the plurality of setting traveling patterns stored in the memory unit **13a**, to select a setting traveling pattern, which coincides with the sensed traveling pattern, of the plurality of setting traveling patterns, and to calculate the command values, i.e., the command values required for operations of the first traveling motor **3** and the second traveling motor **4** to be output to the hydraulic circuit **14** in accordance with the manipulation values of the first electric traveling pedal **11a** and the second electric traveling pedal **11b** sensed by the sensing unit **13b** so that the first traveling motor **3** and the second traveling motor **4** are to be operated in accordance with the selected setting traveling pattern.

The hydraulic circuit **14** is electrically connected to the controller **13**. Thereby, the hydraulic circuit **14** is configured to control a flow rate and flow of operating oil to be supplied to the first traveling motor **3** and the second traveling motor **4** in accordance with the command values transmitted from the controller **13**, thereby driving the first traveling motor **3** and the second traveling motor **4**. Here, since the hydraulic circuit **14** has the same configuration and operation as the main control valve **8** configured to control a flow rate and flow of the operating oil that is to be discharged from the hydraulic pumps **P1, P2** shown in FIG. **7** and is to be supplied to the left and right traveling motors **3, 4**, the detailed description thereof is omitted.

In the below, the control method of the controller that is to be executed when the first traveling pattern is selected by the driver is described with reference to FIGS. **3** to **6**. The reference numerals of the respective configurations are denoted as shown in FIGS. **1** and **2**.

In Examples of the present invention, the first traveling pattern is a traveling pattern for moving forward or backward the excavator in accordance with the manipulation on the first electric traveling pedal **11a** and turning left or right the excavator in accordance with the manipulation on the second electric traveling pedal **11b**.

EXAMPLE 1

When the controller **13** senses the first traveling pattern input to the traveling pattern input means **12** by the driver and the manipulation value output as the first electric traveling pedal **11a** is manipulated forward, the controller **13** calculates a first command value (a command value **1** to be input to the first traveling motor, in FIG. **3**) required for operation of the first traveling motor **3**, as shown in FIG. **3**. Also, the controller **13** calculates a second command value (a command value **1** to be input to the second traveling motor, in FIG. **4**) required for operation of the second traveling motor **4**, as shown in FIG. **4**. Then, the controller **13** transmits the first command value and the second command value to the hydraulic circuit **14** so as to operate the first traveling motor **3** and the second traveling motor **4**. In this case, since the first traveling motor **3** and the second traveling motor **4** are all rotated in the forward direction and the manipulation on the second electric traveling pedal **11b** has not been sensed, the excavator is moved forward. On the contrary, when the first electric traveling pedal **11a** is manipulated backward, the excavator is moved backward through the series of controls of the controller **13** as described above.

EXAMPLE 2

When the controller **13** senses the first traveling pattern input to the traveling pattern input means **12** by the driver and the manipulation value output as the second electric traveling pedal **11b** is manipulated backward, the controller **13** calculates a third command value (a command value **2** to be input to the first traveling motor, in FIG. **5**) required for operation of the first traveling motor **3**, as shown in FIG. **5**. Also, the controller **13** calculates a fourth command value (a command value **2** to be input to the second traveling motor, in FIG. **6**) required for operation of the second traveling motor **4**, as shown in FIG. **6**. Then, the controller **13** transmits the third command value and the fourth command value to the hydraulic circuit **14** so as to operate the first traveling motor **3** and the second traveling motor **4**. In this case, the first traveling motor **3** is rotated in the reverse direction and the second traveling motor **4** is rotated in the forward direction. By the rotations of the first traveling motor **3** and the second traveling motor **4**, the excavator is turned left. On the contrary, when the second electric traveling pedal **11b** is manipulated backward, the excavator is turned right through the series of controls of the controller **13** as described above.

Example 3

When the controller **13** senses the first traveling pattern input to the traveling pattern input means **12** by the driver and the respective manipulation values output as a result of the simultaneous manipulation on the first electric traveling pedal **11a** and the second electric traveling pedal **11b**, the controller **13** calculates a fifth command value required for operation of the first traveling motor **3**. Here, the controller **13** calculates the fifth command value as a sum of the first command value and the third command value. In this case, when the fifth command value calculated as a sum of the first command value and the third command value is a positive value, the first traveling motor **3** is rotated in the forward direction, and when the fifth command value is a negative value, the first traveling motor **3** is rotated in the reverse direction. At this time, an electric signal having a magnitude corresponding to an absolute value of the fifth command value is transmitted from the controller **13** to the hydraulic circuit **14**, so that the first traveling motor **3** is rotated at speed proportional to the electric signal having a magnitude corresponding to the absolute value of the fifth command value.

Also, the controller **13** calculates a sixth command value required for operation of the second traveling motor **4**. Here, the controller **13** selects, as the sixth command value, one of the second command value and the fourth command value. Since the second command value and the fourth command value are all values enabling the second traveling motor **4** to rotate in the forward direction, the controller **13** selects, as the sixth command value, a relatively larger command value of the second command value and the fourth command value.

Then, the controller **13** transmits the fifth command value and the sixth command value to the hydraulic circuit **14**, thereby operating the first traveling motor **3** and the second traveling motor **4**.

As described above, when the first electric traveling pedal **11a** and the second electric traveling pedal **11b** are manipulated at the same time, the fifth command value and the sixth command value required for operations of the first traveling motor **3** and the second traveling motor **4** are determined in

the above-described manner by the controller 13. Therefore, when the manipulation values of the first electric traveling pedal 11a and the second electric traveling pedal 11b are changed, the left and right turning speeds of the excavator can be adjusted. That is, when the first electric traveling pedal 11a and the second electric traveling pedal 11b are manipulated at the same time, a relative turning speed can be increased or decreased, as compared to the left turn or right turn of the excavator in accordance with the third command value and the fourth command value as a result of the single manipulation on the second electric traveling pedal 11b.

Although the present invention has been described with reference to the specific embodiments and the drawings, the present invention is not limited to the embodiments, and a variety of variations and modifications can be made by one skilled in the art of the present invention.

Therefore, the scope of the present invention should not be defined by the above-described embodiments but should be defined by the appended claims and equivalents thereof.

The invention claimed is:

1. A traveling control system for a construction machine comprising:

first and second electric traveling pedals configured to output manipulation values of electric signals in response to driver's manipulation and to thereby operate first and second traveling motors connected thereto, respectively;

a traveling pattern input means equipped in an operator's cab so as to enable a driver to input a traveling pattern of the construction machine;

a controller electrically connected to the first and second electric traveling pedals and the traveling pattern input means, and configured to sense the manipulation value to be output from at least one of the first and second electric traveling pedals and the traveling pattern to be input to the traveling pattern input means and to calculate and output command values required for operations of the first and second traveling motors in accordance with the input traveling pattern; and

a hydraulic circuit electrically connected to the controller and configured to control a flow rate and flow of operating oil to be supplied to the first and second traveling motors in accordance with the command values to be transmitted from the controller, thereby driving the first and second traveling motors, wherein the traveling pattern comprises a first traveling pattern for moving the construction machine forward or backward in accordance with manipulation on only the first electric traveling pedal and turning the construction machine left or right in accordance with manipulation on only the second electric traveling pedal.

2. The traveling control system for a construction machine according to claim 1, wherein the controller comprises:

a memory unit configured to store a plurality of setting traveling patterns,

a sensing unit configured to sense the manipulation values and the traveling pattern, and

a calculation unit configured to compare the sensed traveling pattern and the plurality of setting traveling patterns and to calculate the command values to be output to the hydraulic circuit in accordance with the sensed manipulation values so that the first and second traveling motors are to be operated in accordance with a setting traveling pattern of the plurality of setting

traveling patterns, wherein the setting traveling pattern coincides with the sensed traveling pattern.

3. The traveling control system for a construction machine according to claim 1, wherein the traveling pattern comprises a second traveling pattern for turning the construction machine left, or right in accordance with manipulation on only the first electric traveling pedal and moving the construction machine forward or backward in accordance with manipulation on only the second electric traveling pedal.

4. The traveling control system for a construction machine according to claim 1, wherein responsive to the controller sensing the first traveling pattern input to the traveling pattern input means and the manipulation value output from the first electric traveling pedal, the controller calculates a first command value required for the operation of the first traveling motor and a second command value required for the operation of the second traveling motor and transmits the same to the hydraulic circuit causing the construction machine to move forward or backward.

5. The traveling control system for a construction machine according to claim 4, wherein responsive to the controller sensing the first traveling pattern input to the traveling pattern input means and the manipulation value output from the second electric traveling pedal, the controller calculates a third command value required for the operation of the first traveling motor and a fourth command value required for the operation of the second traveling motor and transmits the same to the hydraulic circuit causing the construction machine to turn left or right.

6. The traveling control system for a construction machine according to claim 5, wherein responsive to the controller sensing the first traveling pattern input to the traveling pattern input means and the manipulation values output from each of the first and second electric traveling pedals, the controller calculates a fifth command value required for the operation of the first traveling motor and a sixth command value required for the operation of the second traveling motor and transmits the same to the hydraulic circuit, causing the construction machine to turn left or right, a relative turning speed thereof being increased or decreased as compared to the left turn or right turn of the construction machine in accordance with the third command value and the fourth command value.

7. The traveling control system for a construction machine according to claim 6, wherein the fifth command value is a sum of the first command value and the third command value.

8. The traveling control system for a construction machine according to claim 7, wherein when the sum of the first command value and the third command value is a positive value, the first traveling motor rotates in a forward direction, and when the sum is a negative value, the first traveling motor rotates in a reverse direction.

9. The traveling control system for a construction machine according to claim 8, wherein an electric signal having a magnitude corresponding to an absolute value of the fifth command value is transmitted from the controller to the hydraulic circuit.

10. The traveling control system for a construction machine according to claim 6, wherein as the sixth command value, a relatively larger command value of the second command value and the fourth command value is selected.
